CAN OPENER

James L. Hvale, Chicago, Ill., assignor to Ekco Products Company, Chicago, Ill., a corporation of Illinois

Application June 13, 1955, Serial No. 36,479

Term of patent 14 years

(Cl. D22—2)

Fig. 1 is a side elevational view of a can opener showing my new design.

Fig. 2 is a similar view taken from the opposite side thereof.

Fig. 3 is a top plan view thereof.

Fig. 4 is an end elevational view thereof as it appears when viewed from the left hand side of Fig. 2; and

Fig. 5 is a side elevational view thereof, with parts broken away for convenience of illustration, showing the jaws in open position.

The dominant features of the design reside in the portions shown in full lines.

I claim:

The ornamental design for a can opener, as shown and described.
